UNITED STATES PATENT OFFICE.

ISAAC E. PALMER, OF MIDDLETOWN, CONNECTICUT.

HAMMOCK.

SPECIFICATION forming part of Letters Patent No. 270,886, dated January 16, 1883.

Application filed October 27, 1882. (No model.)

To all whom it may concern:

Be it known that I, ISAAC E. PALMER, of the city of Middletown, in the county of Middlesex and State of Connecticut, have invented 5 a new and useful Improvement in Hammocks, of which the following is a specification.

It is always desirable to prevent a hammock from folding round the head of a person occupying it, and ordinarily this is prevented by 10 employing a stick or spreader of wood inserted in a pocket, or otherwise secured across one end of the hammock, to hold it extended. If a pillow or bolster is desired, one is placed loosely in the hammock.

15 The object of my invention is to dispense with the spreader of wood above described, and to provide a more convenient arrangement of a pillow or bolster for a hammock; and to this end the invention consists in a hammock 20 having a pillow or bolster extending across one end thereof, and secured thereto at its ends, so as to serve as a spreader to retain the hammock in its extended position. The pillow or bolster may be secured throughout its length 25 transversely to the hammock; or it may be secured thereto at the ends only, and the pillow or bolster may be made complete in itself and secured to the hammock; or it may consist of a pocket formed by folding over and securing 30 a portion of the fabric from which the hammock is made and stuffing such pocket with any desired material.

In the accompanying drawings, Figure 1 represents a perspective view of my improved 35 hammock. Fig. 2 represents a perspective view of one end portion of a hammock provided with a pillow of modified form. Fig. 3 represents a sectional view of one end portion of a hammock, showing the method of forming and 40 attaching the pillow. Fig. 4 represents a sectional view of the piece which is employed in one form of my invention as a pocket or bag which is to be stuffed to form a pillow; and Fig. 45 represents a perspective view of a pillow containing a stretcher or stiffener, of wood or other material, extending lengthwise thereof.

Similar letters of reference designate corresponding parts in all the figures.

A designates the hammock, which may be of 50 any desirable construction; and B designates the suspension-cords, which are secured to

loops a, formed at the ends of the hammock, and at their outer ends are attached to suspension-rings b.

C designates the pillow or bolster, which extends across the end of the hammock, and is secured at its ends to the hammock. This pillow or bolster may be made in any suitable way. In Fig. 1 it is represented as formed by folding over a portion of the fabric of which the hammock is composed to form a pocket or bag, and then stuffing the bag thus formed with any suitable material commonly used for such purposes. The two ends of this pillow or bolster may be secured to the hammock in any 65 way—for example, by means of safety-pins c.

The pillow or bolster C, shown in Fig. 2, is formed by a separate piece, folded and having its edges together, stitched to the hammock at d, entirely across the end of the hammock. The 70 pocket or bag thus formed may be stuffed with any suitable material, and the closing of the ends is completed by buttons f, which may be attached to the hammock and be buttoned in button-holes in both the upper and lower portions of the fabric of the pillow.

The stitching d might be dispensed with and the pillow composed of a bag or tube open at the ends and stuffed. After the pillow is stuffed its ends may be closed and secured to 80 the hammock by the same button, f.

In Fig. 3 I have represented the folded piece which forms the pillow pocket or bag, and the piece in which are formed the loops a is secured to the hammock by a single row of 85 stitches, d.

Fig. 4 represents the piece of material which forms the pillow pocket or bag as folded and ready to be attached to the hammock.

In order that the pillow or bolster may better retain its shape, I may place therein a stretcher, C', of wood or other material, as shown in Fig. 5, which adds stiffness to the pillow or bolster and prevents its deflecting lengthwise.

Where the pillow or bolster is made as shown in Fig. 2 the flattening of the ends where secured to the hammock produces a corresponding widening thereof, and therefore gives the pillow or bolster a very desirable and graceful 100 form and appearance.

The pillow or bolster, when secured across

the end of the hammock, is itself retained in place and prevented from shifting, and it serves as a spreader to keep the hammock extended and prevent its folding about the head of an occupant thereof.

What I claim as my invention, and desire to secure by Letters Patent, is—

1. A hammock having a pillow or bolster extending across one end thereof, and secured thereto at its ends, so as to serve as a spreader, substantially as described.

2. The combination, with a hammock, of a pillow or bolster extending transversely to the hammock, at the end thereof, and stitched or secured thereto from end to end in the direc-

tion of the width of the hammock, and across the ends in the direction of the length of the hammock, substantially as and for the purpose described.

3. The combination, with a hammock, of a 20 pillow or bolster composed of a piece of fabric folded, and having its lapping edges stitched to the hammock in the direction of the width thereof, and a stuffing of any suitable material, substantially as and for the purpose described. 25

ISAAC E. PALMER.
